UNITED STATES PATENT OFFICE

141,447

DESIGN FOR A BALL OPERATED TOY OR SIMILAR ARTICLE

Olai F. Larsen, Jr., Demarest, N. J., assignor to
Noma Electric Corporation, New York, N. Y., a
corporation of New York

Application February 6, 1945, Serial No. 117,785

Term of patent 14 years

(Cl. D34—15)

To all whom it may concern:

Be it known that Olai F. Larsen, Jr., a citizen
of the United States of America and resident of
Demarest, county of Bergen, State of New Jersey,
has invented a new, original, and ornamental
Design for a Ball Operated Toy or Similar
Article, of which the following is a specification,
reference being had to the accompanying draw-
ings, forming part thereof, in which

Fig. 1 is a front view of a ball operated toy
embodying my new design;

Fig. 2 is a top plan view thereof;

Fig. 3 is a rear view thereof; and

Fig. 4 is a side view thereof.

I claim:

The ornamental design for a ball operated toy
or similar article, substantially as shown.

OLAI F. LARSEN, JR.
